FILTER FOR SEDIMENT TRAPS

Richard F. Corwin, East Hampton, N. Y., assignor
to R. A. Corwin & Son, East Hampton, N. Y.

Application October 20, 1947, Serial No. 780,959

2 Claims. (Cl. 210—165)

1

This invention relates to a filter for a sediment trap of the type disclosed in United States Patent 1,040,283, issued October 8, 1912, to E. L. Crum.

Applicant is aware of numerous prior patents pertaining to filters for sediments traps as evidenced by Patent No. 1,630,287, issued May 31, 1927, to S. S. Amdursky; 907,636, issued December 22, 1908, to G. W. Mutz; Patent No. 1,932,676, issued October 31, 1933, to E. A. Rockwell; and Patent No. 1,175,948, issued March 21, 1916, to C. L. French.

While the art so far developed discloses various types and kinds of filters for use in sediment traps, each trap of which applicant is aware requires the use of tools and the like when it becomes necessary or desirable to remove a filter for cleaning or replacement.

The primary object of the present invention is to facilitate the rapid removal and replacement of a filter, should it become necessary to cleanse the filter or introduce a substitute filter in place of one that may have become clogged or otherwise defective.

Another object is to enable filters of different porosities to be introduced into the sediment trap of a fuel line, and thus provide selectivity as to the porosity of the filter finally employed, in accordance with the character of fuel passing through the line.

The above and other objects may be attained by employing this invention which embodies among its features an externally screw threaded head having an axial discharge opening, a bushing extending through the discharge opening for removably supporting the head in concentric relation to and in communication with the discharge passage of a sediment trap, an externally knurled internally threaded retaining ring removably threaded on the head and a filter unit supported by the retaining ring in a position to cover the discharge opening in the head.

In the drawings:

Figure 1 is a side view partially in section of a sediment trap equipped with this improved filter.

Figure 2 is a vertical sectional view taken substantially along the line 2—2 of Figure 1, and

Figure 3 is a horizontal sectional view taken substantially along the line 3—3 of Figure 1.

Referring to the drawings in detail a conventional sediment trap designated generally 10 is provided with a head 11 having an axial discharge passage 12 and an eccentrically located inlet passage 13. The head 11 is also provided with an annular shoulder 14 against which a gasket 15 of any suitable material is seated. Pivots sup-

2

ported on the head 11 as at 16 are the free ends of the legs of a U-shaped yoke 17, the bight portion of which has threaded therethrough the threaded shank 18 of a clamp screw designated generally 19, the head 20 of which is peripherally knurled in a conventional manner. A conventional sediment collecting bowl 21 has its open end seated against the gasket 15, and is held in this position by the clamp screw 19 above referred.

10 The sediment trap above described is of conventional form and in ordinary use the discharge passage 12 thereof is equipped with a filter which serves to prevent solid matter from entering the discharge passage.

As illustrated in Figure 2 the end of the discharge passage which opens into the bowl 21 is internally screw threaded as at 22, and in the preferred form of my invention a bushing 23 having external screw threads at one end is threaded 15 into the threaded opening 22. The end of the bushing opposite its threaded end is provided with an annular outwardly extending flange 24, the perimeter of which is preferably polygonal to enable the bushing to be 20 turned by a wrench or the like. Clamped between the head 11 of the sediment trap and the flange 24 of the bushing 23 is an externally screw threaded head 25 of my improved filter designated 25 generally 26. As illustrated the head 25 is provided with a depending peripheral flange 27, and threaded on the head 25 is a retaining ring 28 provided at one end with an inwardly extending annular supporting flange 29 by means of which 30 my improved filter unit designated generally 30 is supported within the bowl 21 and across the discharge passage 12 in the head 11 of the sediment trap 10. The periphery of the retaining ring 28 is knurled to facilitate its rotation about the head 25 and enable a filter unit 30 easily and 35 quickly to be placed in position in the head or removed therefrom as occasion demands.

The filter unit above referred to comprises a cylindrical body 31 of foraminous material such as screen wire, and one end of the body 31 is 40 closed by a foraminous bottom 32 of like material. Extending outwardly from the opposite end of the body 31 is an annular supporting flange 33, and filling the body is a filtering substance 34 which in its preferred form comprises finely divided steel wool or like inorganic fibrous substance. Overlying the filtering material 34 at the 45 end of the cylindrical body 31 remote from the bottom 32 is a layer of filter cloth 35 which is preferably woven from glass fibers or like inorganic or metallic substance. A foraminous disk

36 of the material from which the cylindrical body 31 is formed overlies the layer 35 of filter cloth, and when the filter unit 30 is in place in the filter this disk 36 lies across the filter unit in spaced relation to the lower end of the bushing 23, to form a chamber 37 which serves as a reservoir for the filtered liquid.

In the preferred form of the invention a gasket 38 is interposed between the upperside of the head 25 and the underside of the head 11 in order to form a fluid tight junction between these parts.

In the installation of this improved filter in a conventional sediment trap, the screw 19 is turned to release the pressure on the bowl 21 and withdrawn far enough to permit the yoke 17 to swing about its pivot 16 so that the bowl 21 may be removed from the head 11. Should the passage 12 be smooth, it is tapped to provide the threads 22 and the bushing 23 with the head 25 resting on the flange 24 is then introduced into the discharge passage 12, and by applying a wrench to the polygonal perimeter of the flange 24 it is evident that a tight junction may be effected between the heads 11 and 25. It is of course preferable that the gasket 38 be employed to prevent the escape of the liquid being filtered into the discharge passage 12 before it passes through the filter. A suitable filter unit is then fitted into the retaining ring 28 with the flange 33 thereof resting on the flange 29 and upon engaging the threads of the ring 28 with the threads of the head 25 and rotating the ring it is evident that the filter unit 30 may easily and quickly be placed in filtering relation with the discharge passage 12 of the sediment trap. Owing to the fact that the ring 28 is externally knurled it is evident that no tools of any kind will be required to rotate the ring about the head 25. After the filter has been placed in position as previously described the bowl 21 is replaced on the head 11 and the yoke 17 is again swung into position so that its bight portion lies beneath the bottom of the bowl whereupon the rotation of the screw 19 may cause it to impinge against the bottom of the bowl and clamp the latter firmly in place on the head 11. The device is then ready for use and it will be evident that liquid flowing into the trap through the passage 13 will descend into the bowl 21 and thence flow upwardly through the filter unit 30 into the discharge passage 12, so that any sediment or foreign matter carried by the fluid into the trap will be deposited in the bowl, and the filter will prevent its discharge through the discharge passage 12.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

- 10 1. A filter for a sediment trap comprising an externally screw threaded head having an axial discharge opening, a bushing extending through the discharge opening for removably supporting the head in concentric relation to and in communication with the discharge passage of a sediment trap, an externally knurled internally threaded retaining ring removably threaded on the head, an inturned annular supporting flange on the ring, a filter unit adapted to cover the discharge opening in the head and an outwardly extending annular flange on the filter unit for cooperation with the inturned supporting flange on the ring in holding the filter unit in proper position on the head.
- 15 2. A filter for a sediment trap comprising an externally screw threaded head having an axial discharge opening, a bushing extending through the discharge opening for removably supporting the head in concentric relation to and in communication with the discharge passage of a sediment trap, an externally knurled internally threaded retaining ring removably threaded on the head, an inturned annular supporting flange on the ring and a removable filter unit held by the flange in filtering relation to the discharge passage in the head.
- 20 3. A filter for a sediment trap comprising an externally screw threaded head having an axial discharge opening, a bushing extending through the discharge opening for removably supporting the head in concentric relation to and in communication with the discharge passage of a sediment trap, an externally knurled internally threaded retaining ring removably threaded on the head, an inturned annular supporting flange on the ring and a removable filter unit held by the flange in filtering relation to the discharge passage in the head.
- 25 4. A filter for a sediment trap comprising an externally screw threaded head having an axial discharge opening, a bushing extending through the discharge opening for removably supporting the head in concentric relation to and in communication with the discharge passage of a sediment trap, an externally knurled internally threaded retaining ring removably threaded on the head, an inturned annular supporting flange on the ring and a removable filter unit held by the flange in filtering relation to the discharge passage in the head.
- 30 5. A filter for a sediment trap comprising an externally screw threaded head having an axial discharge opening, a bushing extending through the discharge opening for removably supporting the head in concentric relation to and in communication with the discharge passage of a sediment trap, an externally knurled internally threaded retaining ring removably threaded on the head, an inturned annular supporting flange on the ring and a removable filter unit held by the flange in filtering relation to the discharge passage in the head.
